Carl Elmer Larson, Indianapolis, Ind.

Application November 13, 1944, Serial No. 116,311

Term of patent 14 years

(Cl. D34—5)

To all whom it may concern:

Be it known that I, Carl Elmer Larson, a citizen of the United States residing at Indianapolis, in the county of Marion and State of Indiana, have invented a new, original, and ornamental Design for a Cabinet for Amusement Device, of which the following is a specification.

In the accompanying drawing, forming a part of the present specification,

Fig. 1 is a perspective view of a cabinet for amusement device, showing my new design; and Fig. 2 is a top plan view thereof on a smaller scale.

I claim:

The ornamental design for a cabinet for amusement device, as shown.

CARL ELMER LARSON.
